UNITED STATES PATENT OFFICE.

HENRY A. WEIHMAN, OF PHILADELPHIA, PENNSYLVANIA, ASSIGNOR TO JOHN F. SIMONS AND THOMAS MADDOCK, OF PHILADELPHIA, PENNSYLVANIA, FREDERICK M. SIMONS, OF SWARTHMORE, PENNSYLVANIA, AND EDWIN S. SIMONS, OF ELIZABETH, NEW JERSEY, TRADING AS SIMONS BRO. & CO., OF PHILADELPHIA, PENNSYLVANIA.

DESIGN FOR A THIMBLE.

No. 37,680.

Specification for Design.

Patented Nov. 21, 1905.

Application filed February 7, 1905. Serial No. 244,666. Term of patent 14 years.

To all whom it may concern:

Be it known that I, HENRY A. WEIHMAN, of the city and county of Philadelphia, State of Pennsylvania, have invented a new, original, and ornamental Design for Thimbles, of which the following is a specification, reference being had to the accompanying drawings, forming part thereof.

Figure 1 is a perspective view of one side

of the thimble, and Fig. 2 is a similar view of the other side.

I claim—

The ornamental design for a thimble as shown.

HENRY A. WEIHMAN.
